UNITED STATES PATENT OFFICE

PAUL R. COLLIER, OF WISSAHICKON, PENNSYLVANIA

TILTING HEADLIGHT FOR SMALL AUTOMOBILES.

Application filed September 5, 1923. Serial No. 460,995.

To all whom it may concern:

Be it known that I, PAUL R. COLLIER, a citizen of the United States, residing at Wissahickon, county of Philadelphia, State 5 of Pennsylvania, have invented new and useful Tilting Headlights for Small Automobiles, of which the following is a specification.

My invention relates to a novel construction of tilting headlights and actuating mechanism therefor for small automobiles, which can be readily adapted to automobile side channels and their adjuncts of any standard or conventional type, and comprises 10 a front headlight shaft or rod which is rotatably mounted in suitable bearings and adapted to be actuated by a direct pull upon suitable actuating means, which may pass through the instrument board of the automobile or if desired can be actuated by the 15 driver's foot.

It further consists of novel means for enabling my invention readily to be attached to existing small automobiles, without alteration.

It further consists of a novel tension or resetting device and a novel means for securing the same in position.

It further consists of other novel features 30 of construction and advantage, all as will hereinafter be set forth and pointed out in the claim.

For the purpose of illustrating my invention, I have shown in the accompanying drawings a typical embodiment thereof which is at present preferred by me, since this embodiment will be found in practice to give satisfactory and reliable results. It is, however, to be understood that the various instrumentalities of which our invention 40 consists can be variously arranged and organized and that my invention is not limited to the precise arrangement and organization of these instrumentalities as herein shown and described.

Figure 1 represents a front elevation of an automobile having thereon tilting headlights and actuating mechanism therefor, embodying my invention.

Figure 2 represents a side elevation of Figure 1, certain of the parts being broken away for the sake of clearness of illustration.

Figure 3 represents on an enlarged scale 55 a side elevation of a portion of the head-

light actuating mechanism and tension devices therefor.

Figure 4 represents a rear elevation of Figure 3.

Figure 5 represents on an enlarged scale 6 a side elevation of a handle or lever for actuating or tilting the headlights, showing the means for locking the same in various positions.

Figure 6 represents a front elevation of 61 Figure 5.

Figure 7 represents a perspective, dia-grammatic view of the operating mechanism for tilting the headlights.

Similar numerals of reference indicate 70 corresponding parts.

Referring to the drawings:—

1 designates a radiator of an automobile, and 2 the side frames or side channels therefor. 3 designates the instrument board, and 75 4 the lamps or tilting headlights, which are mounted upon the arms or brackets 5 through the upper portion of which passes the horizontally disposed headlight shaft 6. 7 designates the tilting arm or crank 80 for tilting the headlights, which is secured fast in position upon the shaft 6, by means of a screw 15. 8 designates bearings at the upper end of the arms or brackets 5, in which the shaft 6 is rotatably mounted. 9 designates 85 the hand lever, and 10 the forwardly extending rod, whose rear end is pivotally attached to the lever 9, the forward end of said rod 10 being pivotally attached to the tilting arm 7. 11 designates a spring having 90 its upper end attached to the arm 17, while its lower end is attached to the eye 12 which passes through the side channels 2 and has its lower end threaded as at 18, and provided with an adjusting nut 19. 13 designates the fender braces. The instru- 95 ment board 3 is provided with a face plate 16, through which the hand lever 9 passes, the latter being provided with notches 14 on the side thereof, which are adapted to 100 engage said face plate 16.

It will be understood in assembling my novel device, that the brackets 5 replace the original rigid brackets, the upper ends of said brackets carrying the members 22 which are screwed into or otherwise fastened to the lamps or headlights 4, said brackets being connected to the lower ends of the fender braces 13 and held in place by the nuts 20, when the parts are assembled.

It will be understood that a pull on the hand lever 9 causes a pull on the rod 10 which rocks the crank arm 7, fast on the shaft 6, being secured thereto by the set screw 15. As the lamps are secured fast to the shaft 6 by means of set screws 21, it will be apparent that the lamps will be tilted to the desired extent upon the actuation of the shaft 6, and the lamps and headlight shaft will move in unison as a unit. As the lamps are tilted forwardly or downwardly to the desired extent, it will be evident that a tension will be imparted to the spring 11, so that when the hand lever 9 is released, the tension of the spring 11 will cause the lamps and their adjuncts instantly to assume their normal position. While I have shown the rod 10 as adapted to be manually operated, it will be evident that it 20 can be foot operated, if desired.

It will be apparent that my device can be readily attached to small cars of any conventional or standard type by merely installing the brackets and the tension devices 25 11 and their adjuncts in position and it will be found to be effective and durable in operation and will not readily get out of order.

It will now be apparent that I have devised new and useful tilting headlights for 30 small automobiles which embodies the features of advantage enumerated as desirable in the statement of the invention and the above description, and while I have, in the

present instance, shown and described a preferred embodiment thereof which will 35 give in practice satisfactory and reliable results, it is to be understood that the same is susceptible to modification in various particulars without departing from the spirit or scope of the invention or sacrificing any of 40 its advantages.

Having thus described my invention, what I claim and desire to secure by Letters Patent is:

In a device of the character stated an instrument board having a hole therethrough, and a face plate bolted thereon, said plate having an aperture therein in register with the hole in said instrument board, a hand-pull lever positioned in said holes and having ratchet teeth therein, adapted to engage with the inner edge of the holes in said face plate, a vehicle frame, brackets mounted thereon, a head-light shaft rotatably mounted in the upper end of said brackets, 55 headlights mounted on said shaft and movable in unison therewith, a crank arm fast on said headlight shaft, a connection from said crank arm to said hand-pull lever positioned in said instrument board, which rod is 60 pivoted to said hand-pull lever, a lateral arm projecting from said shaft, an eye adjustably mounted in said vehicle frame, a spring intermediate said arm and eye, and an adjusting nut for said eye.

PAUL R. COLLIER.
